US0D1099102S

(12) **United States Design Patent** (10) Patent No.: **US D1,099,102 S**
(45) Date of Patent: ** Oct. 21, 2025

(54) **PROTECTIVE CASE FOR ELECTRONIC DEVICES**

(71) Applicant: **MOBILIS DEVELOPMENT**, Chavanod (FR)

(72) Inventors: **Floriane Robbaz**, La Balme de Sillingy (FR); **Marc Fernandez Lado**, Annecy (FR)

(**) Term: **15 Years**

(21) Appl. No.: **35/523,427**

(22) Filed: **Nov. 28, 2024**

(80) **Hague Agreement Data**

Int. Filing Date: **Nov. 28, 2024**

Int. Reg. No.: **DM/242842**

Int. Reg. Date: **Nov. 28, 2024**

Int. Reg. Pub. Date: **Dec. 27, 2024**

(30) **Foreign Application Priority Data**

Jul. 5, 2024 (EM) 015065586-0001

(51) **LOC (15) Cl.** **14-02**

(52) **U.S. Cl.**

USPC **D14/440**

(58) **Field of Classification Search**

Primary Examiner — Cynthia R Underwood

(57) **CLAIM**

The ornamental design for protective case for electronic devices as shown and described.

DESCRIPTION

1. Protective case for electronic devices
  - 1.1 : Front
  - 1.2 : Back
  - 1.3 : Front Perspective
  - 1.4 : Bottom Perspective
  - 1.5 : Top Perspective
  - 1.6 : Right Side Perspective
  - 1.7 : Left Side Perspective
